United States Patent Office

Des. 204,273
Patented Apr. 5, 1966

204,273

BRAILLE DESK

Paul E. Hadlick, Jr., 11527 Monticello Ave.,
Silver Spring, Md.

Filed Mar. 12, 1965, Ser. No. 84,245

Term of patent 14 years

(Cl. D33—7)

FIG 1

FIG 2

FIG 3

FIG 5

FIG 4

FIGURE 1 is a top perspective view of the braille desk, showing my new design;

FIGURE 2 is a bottom perspective view thereof;

FIGURE 3 is a front elevational view thereof;

FIGURE 4 is an end elevational view thereof; and

FIGURE 5 is a rear elevational view thereof.

The side of the desk not shown is the same in appearance as the side shown.

I claim:

The ornamental design for a braille desk, as shown and described.
